UNITED STATES PATENT OFFICE.

JAMES C. WOODSON, OF MANSFIELD, OHIO, ASSIGNOR TO WESTINGHOUSE ELECTRIC
PRODUCTS COMPANY, A CORPORATION OF MICHIGAN.

ELECTRIC BAKE OVEN.

1,425,620.

Specification of Letters Patent. Patented Aug. 15, 1922.

Application filed June 25, 1921. Serial No. 480,289.

To all whom it may concern:

Be it known that I, JAMES C. WOODSON, a citizen of the United States, and a resident of Mansfield, in the county of Richland and State of Ohio, have invented a new and useful Improvement in Electric Bake Ovens, of which the following is a specification.

My invention relates to electrically heated ovens and particularly to electrically heated 10 bake ovens of the reel type, and it has for its object to provide a bake oven of the above indicated character having a plurality of independently removable heat-insulating panels secured to a skeleton frame.

It is highly desirable, in the ovens of the above indicated character, to employ a construction which permits of assembling the oven at the factory and of shipping it in this condition: In case the opening or doorway 20 available for its installation is not sufficiently large to permit of it being moved therethrough in its entirety, it becomes highly desirable to disassemble the oven into the smallest possible number of parts to permit 25 of moving the same through the available doorway, in order that the labor of disassembling or reassembling may be as small as possible.

In practicing my invention, I provide a 30 base frame composed of steel members of standard shape and dimensions and mount thereon a heat-insulated bottom panel of the oven provided with members for supporting substantially the entire weight of the rest of 35 the oven. I provide a plurality of two-part skeleton end-frames and maintain the same in spaced-apart relation by means of suitable spacing members. A bearing is provided in each of the end frames in which a 40 rotatable shaft is located, upon which is secured a plurality of reels having a plurality of trays mounted therebetween, upon which the material to be baked may be placed and revolved in the oven chamber by suitable 45 driving mechanism.

I provide a plurality of independently removable heat-insulated double-wall panels which are suitably secured to the end frames. Suitable spacing strips are provided between the abutting bevelled edges of the 50 panels. White enamel panels are provided for the outside of each of the heat-insulated panel members, the abutting or adjacent

edges being covered by means of suitable metal finishing strips.

A door panel is provided with a counter-weight to permit of opening the same easily and quickly, the inner surface of the door panel, when opened, providing a shelf in front of the oven to facilitate the insertion 60 and removal of the material.

An electric heating means is located at the bottom of the oven chamber and may be controlled in any suitable or desired manner to automatically maintain the temperature at any predetermined value.

In the drawings:

Figure 1 is a view, in vertical lateral section, of a reel type bake oven embodying my invention;

Fig. 2 is an enlarged view of a bottom portion of the oven illustrated in Fig. 1;

Fig. 3 is a view, in longitudinal vertical section, of a reel-type oven embodying my invention;

Fig. 4 is a top plan view of a bottom back panel constituting a part of the oven embodying my invention;

Figs. 5 and 6 are views, in side and in end elevation, respectively, of the panel illustrated in Fig. 4;

Fig. 7 is a top plan view of one of the half end panels;

Fig. 8 is a top plan view of the complementary half end panel;

Figs. 9 and 10 are views, in end elevation, of the panels illustrated in Figs. 7 and 8, respectively, and

Fig. 11 is a schematic view, in horizontal section, illustrating the interfitting of the end and the side panels.

A base frame for the oven comprises a plurality of supporting members 1, which are suitably connected by means of a plurality of longitudinally extending angle members 2 bolted thereto, and laterally extending angle members 3. A plurality of members 4, substantially of T-shape, are secured, at their ends, to the members 2 intermediate the supports 1.

A bottom panel 5 of the oven is located on the built-up base frame. The panel 5 comprises, in general, an upper metal sheet 6 and a lower-metal sheet 7 maintained in spaced-apart relation by means of a plurality of laterally extending spacing members.

8, substantially of channel section. Adjacent each end of the panel 5 is located a member 9, also of channel section, but heavier than the members 8 and adapted to support the weight of substantially all of the rest of the oven. Further detailed description of the panel will be hereinafter set forth.

A plurality of skeleton end frames 10 is provided, each end frame comprising two halves, bolted together by a plurality of bolts 11, the two halves forming a member of distorted octagonal contour, the vertical dimension being substantially greater than the horizontal dimension. The two end frames 10 are maintained in spaced-apart relation by means of a plurality of members 12 of angle section, bolted thereto at the bottom thereof, members 13 of angle section bolted thereto at the top thereof and a plurality of members 14 substantially of channel section bolted thereto at the sides thereof.

A bearing shell 15 is located in each of the end frames 10 and supports a rotatable shaft 16. A plurality of reel frames 17 are mounted in spaced relation on the shaft 16 and suitably secured thereto by means of set screws 18. A plurality of trays 19 are suspended between the reel frames 17 by means of bolts 19^a, secured thereto. The construction employed is such as to permit of rotating the shaft 16 and the reel frames 17 to revolve material placed upon the shelves 19 in the oven chamber, the material remaining in a substantially horizontal position.

Suitable driving mechanism for the above described reel structure comprises a motor 20 mounted upon a bracket 21 secured against one end of the oven, and a speed-reducing train of gears (not shown), located in a casing 22 and serving to operatively connect the motor shaft and the shaft 16, a relatively high-speed reduction being employed. A hand wheel 23 is suitably connected to the speed-reducing mechanism to permit of rotating the shaft 16 by hand in case this becomes necessary because of the failure of the motor 20, or for any other reason.

A plurality of electric heating elements 24 are located in the bottom of the oven chamber and may comprise any suitable or desired combination of resistor elements 25 and supporting frames 26. In order to equalize the heating effect of the elements 24 at each end of the oven chamber, I provide a baffle-plate structure 27 which is more particularly described and claimed in my copending application, Serial No. 474,726, filed June 3, 1921.

A plurality of heat-insulated panels for the sides of the oven, are secured to the end frames 10 and comprise a bottom

back panel 28, a center back panel 29, an upper back panel 30, a top panel 31, an upper front panel 32, a plurality of front-center panels 33 and 34 and a bottom front panel 35. The ends of the oven are closed by a plurality of end panels, the right half panel at each end being substantially identical and comprising a panel member 36. The left half panels at each end are substantially alike, comprising a panel member 37, both the panel members 36 and 37 being adapted to cooperate with each other to form a member of substantially the same contour as that of the end frames 10.

The front center panels 33 and 34 are spaced apart to form an opening for a door 38 which is provided with hinge members 39, a handle member 40 and a counter-weight 41 which is adjustably mounted on a bar 42 secured against the inside of the door panel 38. The location and weight of the member 41 is such as to substantially balance the weight of the door panel 38 in any position thereof.

Figs. 4, 5 and 6 illustrate, in detail, the construction of the bottom back panel and, as the other side panels are of substantially similar construction, it is believed that a description of the other panel is unnecessary. The panel 28 comprises a top plate 43 which is formed with integral, angularly return-bent side and end portions 44, and a bottom plate 45 which is also provided with angularly, return-bent side and end portions 46, the portions 44 and 46 being adapted to operatively engage each other over a portion of their width. This construction provides a hollow-double-wall panel member which is filled with a suitable heat-insulating material 47, such as mineral wool, which may be so cut as to fit snugly within the double-wall structure hereinbefore described.

Means for spacing apart the plates 43 and 45 comprise a plurality of members 48 substantially of channel section. The top sheet 43 may be secured to the channel members 48 by means of a plurality of rivets 49.

In constructing the panels, the channel members 48 are secured to the top sheet 43 as above described, then the heat-insulating material 47 may be placed in position, after which the bottom sheet 45 may be placed in position on the top sheet 43. The overlapping edges 44 and 46 are secured together by means of a plurality of screws 50, the same means being employed to secure the sheet 43 against the channel members 48.

A plurality of openings 51 are provided through the panel to permit of passing bolts 52 through the panel to secure the same against the end frames 10, hereinbefore described.

An opening 53 is provided at substantially the middle of the panel 28 to permit of passing therethrough supply-circuit conductors (not shown), for energizing the 5 heating elements 24.

The end panels illustrated in Figs. 7, 8, 10 and 10 comprise substantially the same parts as hereinbefore mentioned, in connection with the panel 28, the outline of 15 each of the panels being, of course, different to conform to the contour of the oven chamber and of the end frames 10. Instead of a plurality of members 48 of channel section, only one such member is employed, 20 but a plurality of relatively short members 54, substantially of channel section, are employed and are located in spaced relation in each of the panels, otherwise the construction is identical with that heretofore described.

A recess 55 in the inner edge of the panel member 36 and a recess 56 in the inner edge of the panel member 37 cooperate to form an opening, in which the bearing of the reel 25 mechanism is located, the dimensions and contour of the opening being such as to closely surround the bearing, to prevent the escape of heated fluid from the interior of the oven.

30 The bevelled edges of the panel member 36 extend parallel to each other, while the bevelled edges of the panel member 37 extend angularly to each other, the relation of these panels to each other, and to the 35 side panels being substantially as illustrated in Fig. 11.

As has hereinbefore been described, the panels are secured to the end frames 10 by means of a plurality of bolts 52 which are 40 located in the openings 51. The dimensions of the panels are so selected that the edges do not operatively engage each other but leave a space 57 which may be filled with a strip 58 of a suitable heat-insulating material.

In order that the adjacent edges of the double-wall panel members may be caused to approach each other to the fullest extent allowed by the bolts 52 securing the 50 panels against the end frames 10, further provision is made comprising a plurality of bolts 59 angularly disposed relatively to the flat surface of the panel members 30 and 32 and adapted to engage, at their inner 55 ends, the angle members 13. Hook bolts 60 are provided to draw the upper edge of panel member 29 towards the bottom edge of panel 30 the upper edge of panel 33 against the bottom edge of the panel 32 and 60 the upper edge of panel 28 against the bottom edge of the panel 29. Bolts 61 are provided adjacent the bottom edge of panels 28 and 35 angularly disposed relatively to the flat surface of the panels, and adapted to 65 operatively engage, at their inner ends, with

the angular members 12 to draw the lower edges of the panels tightly against the end frames 10.

The surface of each of the panels is covered with a white enamelled panel member 70 62, each of which is of suitable contour to cover substantially the entire outer surface of the panel.

A plurality of finishing strips 63 are located to cover the adjacent edges of the 75 panels and particularly of the white-enamel panel members 62 to present a pleasing and finished appearance to the structure.

In building up the entire oven structure, the base frame hereinbefore described, may 80 be built up first and the bottom panel 5 placed in its proper operative position. The end frames 10 may now be placed thereon and bolted thereto by means of the bolts 9^a, and the members 12, 13 and 14 may be suitably bolted to the end frames 10. The entire reel mechanism, comprising the shaft 16, the reel frame 17 and the associated trays 19, may be placed in position. The bottom panels 28 and 35 may be placed in 90 position and bolted on, after which the panels 29, 34, 33, 30, 32 and 31 may be placed in position in the order named and be secured by bolts, as hereinbefore described. The end panels 36 may be placed in position, after which the panels 37 may be placed in position and bolted.

The heating elements 24 may be placed in position before the panels 28 and 35 are mounted or they may be placed in position 100 after all of the panels have been bolted in place.

After all of the bolts holding the panels against the end frames have been placed in position and tightened, the panels 62 may 105 be placed in their proper operative position and the finishing strips 63 may be placed in their proper operative position and secured by any suitable means, such as screws.

After the white-enamel panels have been 110 placed in position at the ends of the oven, the driving mechanism hereinbefore described, including the motor 20, mounted on the bracket 21, may be placed in position and suitably adjusted.

The door panel 38 and its associated counterweight 41 may now be placed in position.

It may be noted that the device embodying my invention provides a reel-type bake oven comprising a plurality of frame and of 120 panel members which may be assembled in the factory to form a complete oven. This oven may be shipped as a complete unit and may be moved to its operating position as such, but, if the opening provided is not sufficiently large to permit of passing the oven therethrough, it may be disassembled as follows: remove a portion of the finishing strips and the top and end panels. Remove the bolts 11 and the bolts 9^a, after which one- 125 130

4
half of the end frame 10, at each end of the oven, together with the associated panels, comprising, respectively, the panels 28, 29 and 30, or the panels 32, 33, 34, 35 and the 5 door 38 may be removed from the bottom panel and the base frame, it being understood that the reel mechanism is disassembled to whatever extent is necessary to permit of moving it through the opening 10 provided. The base frame and the bottom panel may then be moved through the opening as a unit, as well as each half-end-frame structure, with the bolted side panels. The parts may now be reassembled as hereinbefore described, after which the oven is ready for operation.

My improved invention thus provides equally removable panels which may be removed independent of each other whenever 20 this becomes necessary or desirable. My oven further provides a built-up heat-insulated structure of relatively light weight, permitting of its being transported as a unit.

25 Various modifications may be made in the device embodying my invention without departing from the spirit and scope thereof, and I desire that only such limitations shall be placed thereon as are imposed by the 30 prior art or are specifically set forth in the appended claims.

I claim as my invention:

1. A reel-type bake oven comprising a reel mechanism in said oven, a supporting frame, 35 a double-wall bottom panel located on said frame and a plurality of members in said panel for spacing apart the walls thereof and for supporting said reel mechanism.

2. A reel-type bake oven comprising a 40 supporting frame, a plurality of end frames, a reel mechanism rotatively mounted in said end frames, a double-wall bottom oven panel located on said supporting frame and a plu-

rality of members of substantially channel shape in said bottom panel for spacing apart 45 the walls thereof, certain of said members being adapted to support said end frames and reel mechanism.

3. A bake oven comprising a pair of end frames, members for spacing said end frames apart, a plurality of top, side and end panels operatively associated with said end frames and spacing members, means associated with each of said panels for drawing said panels closely against said end frames and said 55 spacing members, a supporting frame, a bottom panel located on said supporting frame, and a plurality of members in said bottom panel for supporting the weight of said end frames, spacing members, top, side and end 60 panels.

4. A bake oven comprising a pair of end frames, members for spacing said end frames apart, a supporting frame, a bottom panel located on said supporting frame, 65 means for securing said end frames and bottom panel to said supporting frame, and a plurality of end, top and side panels adapted to be secured to said end frames and independently removable therefrom. 70

5. A bake oven comprising a pair of end frames, members for spacing said end frames apart, a supporting frame, a double-wall bottom panel having beveled edges and secured to said supporting frame, a plurality 75 of double-wall side, top and end panels each having beveled edges and adapted to be secured to said end frames in such manner as to cause certain edges of said panels to operatively engage each other, and means for securing said panels to said end frames. 80

In testimony whereof, I have hereunto subscribed my name this 15th day of June, 1921.

JAMES C. WOODSON.
